[57] CLAIM

The ornamental design for a earring fastening apparatus, as shown and described.

DESCRIPTION

FIG. 1 is a front side perspective exploded view of a first embodiment of the earring fastening apparatus of the present invention.

FIG. 2 is a front side perspective assembled view of the embodiment of FIG. 1.

FIG. 3 is a side perspective assembled view of the embodiment of FIG. 1.

FIG. 4 is a rear plan view of the embodiment of FIG. 1.

FIG. 5 is a front plan view of the embodiment of FIG. 1.

FIG. 6 is a side cross-sectional assembled view of the embodiment of FIG. 1.

FIG. 7 is a front side perspective exploded view of a second embodiment of the earring fastening apparatus of the present invention.

FIG. 8 is a front side perspective assembled view of the embodiment of FIG. 7.

FIG. 9 is a side perspective assembled view of the embodiment of FIG. 7.

FIG. 10 is a rear plan view of the embodiment of FIG. 7.

FIG. 11 is a front plan view of the embodiment of FIG. 7; and,

FIG. 12 is a side cross-sectional assembled view of the embodiment of FIG. 7.

It being understood that the broken lines are for illustrative purposes only.
